Edward S. Reed,
Attorney

UNITED STATES PATENT OFFICE.

JAMES G. MATTHEWS, OF SOUTH BEND, INDIANA.

PLAYING-CARD.

1,194,858.

Specification of Letters Patent. Patented Aug. 15, 1916.

Application filed October 25, 1915. Serial No. 57,640.

To all whom it may concern:

Be it known that I, JAMES G. MATTHEWS, a citizen of the United States, residing at South Bend, in the county of St. Joseph and State of Indiana, have invented certain new and useful Improvements in Playing-Cards, of which the following is a specification, reference being had therein to the accompanying drawing.

10 This invention relates to playing cards and the object of the invention is to provide a playing card of such a character as to facilitate the handling of the pack or deck of cards.

15 Playing cards are of various kinds, the best known being the ordinary "pedro deck", which comprises 4 suits, each designated by a symbol, the symbols being hearts, diamonds, clubs and spades. The cards are 20 usually rectangular in shape with the symbols on the body portion thereof, and indexes on diagonally opposite corners thereof. In addition to this particular type of playing card, there are various other playing 25 cards with which different games may be played, but which are similar to the pedro deck in their general shape and in the manner in which they are handled.

My invention is applicable to any playing 30 card of this general character, and in carrying out the main purpose thereof it is a further object to provide a playing card of such a shape that the pack, or deck, can be quickly and easily assembled with the several 35 cards in proper alinement; that the deck can be more easily shuffled; that the cards can be readily spread into fan shape in the player's hand, and when so spread will be symmetrically arranged; and that a 40 selected card may be withdrawn from the hand with less danger of displacing other cards in the hand.

It is also an object of the invention to provide a playing card having the indexes 45 so arranged thereon that any edge of the card may constitute the base thereof; and that, when the deck is assembled, there will always be an index upon each card arranged to be exposed by spreading the cards into a 50 fan shape.

Other objects of my invention, and other advantages resulting therefrom, will appear as it is described in detail.

In the accompanying drawing, Figure 1 is 55 a detail view of a playing card constructed in accordance with my invention; Fig. 2

shows a group of cards in the process of being brought into alinement; Fig. 3 shows a group of cards spread into fan shape, as they are held in the hand of the player; 60 and Fig. 4 shows the invention applied to cards used for playing games of a different kind.

In these drawings I have shown, in Figs. 1 to 3 inclusive, the invention as applied to 65 the cards of the pedro deck, while in Fig. 4 I have shown the invention as applied to the cards of the game known as "pit". In both instances the invention is exactly the same, the cards differing only in the character of 70 the symbols which they bear.

In carrying out the invention I utilize an equilateral card and preferably so shape the card that the corners, or angles, formed by the intersections of the edges thereof are 75 less than a right angle, and I have found that an equilateral triangle is the most satisfactory shape. Such a card is shown in the drawings at 1 and has each of its three edges of substantially the same length and 80 preferably has its corners rounded as shown. The several edges of each card being of the same length, it is obvious that when the cards are gathered up and dropped on edge 85 on the table, they can be quickly and easily brought into alinement by a lateral movement thereof, that is, by merely pushing them together edge-wise. In this manner the disadvantage and difficulty experienced in alining the cards of the ordinary deck 90 is entirely overcome, as the cards naturally aline themselves and it is not necessary for the player to adjust his cards or straighten them up, to arrange the long edges of all the cards parallel. Such a card is very 95 easily shuffled, the narrow point, or corner, being readily insertible between the edges of other cards, and the shape is such that the handling and shuffling can be accomplished in substantially the usual manner. 100

Further, the shape of the card lends itself exceedingly well to the manipulating of the cards in the hands of the player. Each of the three corners of the card has a separate function when they are placed in the hand 105 after the manner shown in Fig. 3. The lower left hand corner is grasped by the hand of the player and serves as a hub, or a supporting center about which the card is turned to adjust it in spreading the cards 110 into fan shape. The lower right hand corner projects in such a manner that it may

be readily grasped to manipulate the card about the support formed by the left hand corner. The upper corner, or the apex of the card, is so arranged that the index which 5 is placed thereon, as is hereinafter described, can be very readily exposed. Further, the shape of the cards is such that when spread out in fan shape, the hand is symmetrical in form and of an attractive appearance, 10 there being no parts or corners of the cards to project outward. When the cards are held in the hand as shown in Fig. 3, a selected card may be very readily removed with little danger of displacing other cards 15 in the hand because of the comparatively small surfaces which are in contact and the narrow, tapering shape of that portion of the card which is grasped by the hand of the player.

20 The symbols may be arranged upon the cards in any suitable manner as here shown, however, I have arranged them in the central portion of the card and have employed a single symbol 2 for each card. I have placed an index 3, which usually comprises 25 a symbol indicating the suit of the card and a letter or number indicating its value, in each corner of the card. This index being preferably arranged along that edge of the 30 corner, which when the corner is uppermost, will be the left hand edge thereof. Thus, a slight lateral displacement of the cards will serve to expose the index. This arrangement of the indexes enables any edge of the card

to constitute the base thereof, and the cards 35 can be gathered up and brought into assembled positions with the assurance that each card will have an index in a position to be exposed when the cards are spread in the hand. Moreover, the shape of the card, 40 particularly when combined with the arrangement of the index, enables a large number of cards to be held in the hand without inconvenience.

While I have shown and described one 45 embodiment of my invention, I wish to be understood that I do not desire to be limited to the exact details of construction and arrangement shown and described, as various modifications will occur to a person 50 skilled in the art.

Having now fully described my invention, what I claim as new and wish to protect by Letters Patent is:—

1. A triangular playing card having similar indexes in the angles thereof.
2. A playing card having a plurality of straight intersecting edges of substantially equal length and having similar indexes in the several corners thereof.
3. A playing card having three sides of substantially equal length, having similar indexes in the angles thereof and having a symbol arranged in central portion thereof.

In testimony whereof I have affixed my 65 signature hereto.

JAMES G. MATTHEWS.
